Primary Examiner — Cynthia Underwood(74) *Attorney, Agent, or Firm* — Seyfarth Shaw LLP**CLAIM**

The ornamental design for a hinge, as shown and described.

DESCRIPTION

FIG. 1 is a front perspective view of an embodiment of our hinge;

FIG. 2 is a top plan view thereof;

FIG. 3 is a front elevation view thereof;

FIG. 4 is a right-side elevation view thereof;

FIG. 5 is a rear elevation view thereof;

FIG. 6 is a left-side elevation view thereof;

FIG. 7 is a bottom plan view thereof; and,

FIG. 8 is a cross-section view thereof taken from line **8-8** in FIG. 2.

The broken lines depict environmental subject matter only and form no part of our claimed design.

The dot-chain lines illustrate a border of the claimed subject matter and form no part of our claimed design.
